EXPANDABLE CORE-FORMER

Leonard D. Long, P.O. Box 288, 2110 Mt. Pleasant St.,
Charleston, S.C.
application Ser. No. 51,972, Aug. 25, 1960, now Patent
No. 3,210,039, dated Oct. 5, 1965, which is a division of
application Ser. No. 51,972, Aug. 25, 1960, now Patent
No. 3,090,093, dated May 21, 1963. Divided and this
application July 19, 1965, Ser. No. 473,045
6 Claims. (Cl. 249—181)

This invention relates to a core-former, and more particularly to an expandable core-former for producing cores in cored building blocks and the like. This application is a division of my copending application Serial No. 215,218, filed August 1, 1962, now Patent No. 3,210,039, which is a division of my application Serial No. 51,972, filed August 25, 1960, now Patent No. 3,090,093, issued May 21, 1963.

It is an object of my invention to provide a core-former which can be expanded by a rotational thrust force, which can be uniformly expanded throughout its length, which can be expanded against the action of substantial counter-forces, which can be maintained in a fixed position and orientation during its expansion, and which will prove sturdy and durable in use.

In accordance with one form of my invention, the core-former comprises a plurality of core segments having inwardly presented thrust-receiving faces which are operatively engaged by thrust-transmitting cam means mounted on a first shaft interposed between the core segments and rotatable to cause said cam means to move the core segments into spaced relation to each other for expanding the core-former. Conveniently, the core segments are operatively interconnected whereby upon reverse rotation of said first shaft said core segments will be moved toward each other to collapse the core-former.

A plurality of face plates are operatively connected to the several core segments to bridge the spaces between said segments and prevent the material being cored from entering into the interior of the core-former from the sides thereof when said core-former is expanded. Preferably, the opposed ends of the core segments are also operatively connected to plate means which prevent the material being cored from entering into the interior of the core-former from the ends thereof. Conveniently, a pilot is provided at one end of the core-former for guiding the core-former into a mold and releasably retaining it in a fixed position therein, and the plate means at the opposite end of the core-former is connected to a second shaft for moving the core-former into and out of operative position in a mold.

Other objects and features of my invention will become apparent from the more detailed description which follows and from the accompanying drawings, in which:

FIG. 1 is a vertical section through an expandable core-former embodying my invention;

FIG. 2 is a horizontal section taken on the line 2—2 of FIG. 1;

FIG. 3 is a horizontal section similar to FIG. 2, but showing the core-former in expanded position;

FIG. 4 is a horizontal section taken on the line 4—4 of FIG. 1;

FIG. 5 is a horizontal section taken on the line 5—5 of FIG. 1 with portions thereof broken away;

FIG. 6 is a vertical section of the core-former shown in FIG. 1, but showing said core-former in expanded position;

FIG. 7 is an enlarged fragmentary isometric view of one of the core segments shown in FIG. 1;

FIG. 8 is an enlarged fragmentary isometric view of the cams shown in FIG. 1;

2

FIG. 9 is a bottom plan view of the spider plate shown in FIG. 5;

FIG. 10 is a top plan view of the pilot plate shown in FIG. 11 and

FIG. 11 is a bottom plan view of the core-former shown in FIG. 1, but with portions thereof broken away.

My core-former is adapted to be used in combination with an apparatus of the type disclosed in my Patent No. 3,090,093, issued May 21, 1963, for producing molded components having cores formed therein. The construction of my core-former is such that it can be inserted in a collapsed condition into an appropriate mold prior to the addition of the material to be molded, and then expanded to compress said material against the inwardly presented mold walls. This permits the formation of high-density molded articles having cores formed therein.

For ease of description, the core-former is described herein as being used to produce cored building blocks formed from an aggregate mixture. It is to be understood, however, that my core-formers can be used for producing various other types of cored elements.

My core-former requires the thrust-transmitting shaft 580 to rotate through an angle of 90°. As shown in FIG. 1, the core-former is carried on a vertical extending shaft 575 for moving the core-former into and out of a mold. A spider plate 576 is rigidly mounted on one end of the shaft 575 for connecting the core-former to said shaft, and as shown in FIG. 5, said plate 576 has a lateral extent substantially as large as the lateral extent of the core-former in its collapsed position, and has its edges beveled, as at 578. The core-former is expanded by means of the rotatable shaft 580 extending upwardly through the shaft 575 for connection to a rotational power source.

As shown in FIG. 2, the core-former is provided with elongated core segments 582 disposed at the four corners of the core-former and slidably connected to the plate 576. To this end, a T-shaped key 584 is mounted on the upper end of each of the core segments 582 and is slidably received in a T-shaped keyway 586 formed in the lower face of the plate 576. As shown in FIG. 9, the keyways 586 are disposed on the oblique axes of the plate 576 and extend inwardly from each of its corners.

Similarly, a T-shaped key 588 is mounted on the lower face of each of the core segments 582 and is slidably received in a T-shaped keyway 590 disposed on an oblique axis of the upper face of a pilot plate 592. A rectangularly shaped pilot 594 extends downwardly from the pilot plate 592 for reception in an opening in the bottom of a mold upon movement of the core-former into said mold, said pilot engaging the faces of said opening to prevent the core-former from rotating in the mold. As shown in FIG. 1, a bolt 591 extends upwardly through the pilot to rotatably connect the pilot plate 592 to the lower end of the shaft 580. Conveniently, the pilot plate 592 has its edges beveled, as at 598, and has a lateral extent corresponding to the lateral extent of the spider plate 576.

As shown in FIG. 3, the inwardly presented faces of each of the core segments comprises a plurality of vertically spaced thrust-receiving faces 600 which project inwardly toward the vertical core-former axis. Between each of the thrust-receiving faces 600, the core segment is recessed as at 602. The core segments 582 are arranged in diagonally opposed pairs 582A and 582B with the thrust-receiving faces 600 of the pair 582A being disposed in horizontal alignment with the recesses 602 in the pair 582B, and vice versa.

The shaft 580 extends downwardly through the shaft 575 and carries two sets of double-lobed cams 604 and 606 mounted on its lower portion and engageable with the core segments 582. As shown in FIG. 2, the set of cams 604 lies on one oblique axis of the core-former when it

is in collapsed position for reception in the recesses 602 in the pair of the diagonally opposed core segments 582B. The other set of cams 606 is disposed 90° out of alignment with the set of cams 604, and is alternately mounted on the shaft 580 between the cams 604 so that each of the cams 606 lies in the recesses 602 of the other pair of diagonally opposed core segments 582A. In this manner, the cams 604 and 606 are both disposed in the recesses 602 of the several core segments when the core-former is in collapsed position with the adjacent faces of adjacent core segments being disposed in abutting relationship. As shown in FIG. 2, the thrust-receiving faces 600 on the core segments are curved inwardly toward the vertical core-former axis along the same radius of curvature as the central portion of the cams 604 and 606 interconnecting the cam lobes to thus minimize the lateral extent of the core-former in its collapsed position.

As shown in FIGS. 1 and 7, the series of alternate thrust-receiving faces 600 and recesses 602 on each of the core segments is interrupted adjacent the upper and lower ends of the core segment by a pair of inwardly projecting sleeve blocks 610. Each of said sleeve blocks is provided with openings 612 for the reception of a pair of horizontally disposed sleeves 613 slidably interconnecting the adjacent core segments 582A and 582B. As shown in FIG. 4, one end of each of said sleeves is connected to one of the core segments in each pair of adjacent core segments by a countersunk bolt 614 around which one end of a coil spring 616 is received. The opposite end of said spring is connected to a countersunk bolt 618, countersunk in a face plate 620 rigidly mounted on the core segment adjacent the core segment in which the bolt 614 is received. In this manner, each of the springs 616 biases a pair of adjacent core segments toward each other to urge the core-former into its collapsed position.

Each of the face plates 620 is mounted on one of the core segments 582 as by countersunk screws 622, and serves to prevent the entry of aggregate into the core-former when it is in expanded position. As shown in FIG. 3, each of the face plates 620 has a width corresponding to the width of the core-former in collapsed position so that it bridges the space between a pair of adjacent core segments 582A and 582B when the core-former is in expanded position. Extending inwardly from the upper and lower ends of the face plates are top and bottom cover plates 624 and 625, respectively, extending inwardly over the outer faces of the spider plate 576 and pilot plates 592 to abut the shaft 575 and pilot 594. In order to guide the movements of the cover plates during expansion and contraction of the core-former, the outer faces of the spider and pilot plates are provided with pluralities of keyways 626 which slidably receive keys 630 mounted on the inner faces of each of the cover plates 624 and 625. As shown in FIGS. 5 and 11, the keys 626 and keyways 630 are disposed at a 45° angle to the transverse core-former axes, the angle of movement of the face plates 620 and core segments 582. Conveniently, the edges of the face plates 620 and cover plates 624 and 625 are beveled, as at 627, to screed any aggregate from the surfaces on which they slide during contraction of the core-former.

Thus, the operation of the core-former illustrated in FIGS. 1-11 may be described as follows: The shaft 575 is moved axially to position the core-former in a mold, with the pilot 594 seating said core-former in an operative position therein. When the shaft 580 is rotated through a 90° angle in a clockwise direction as viewed in FIG. 26, the cams 604 will rotate into engagement with the thrust-receiving faces 600 on the opposed pair of core segments 582A, and the cams 606 will be rotated into engagement with the thrust-receiving faces 600 on the diagonally opposed pair of core segments 582B. As shown in FIG. 3, movement of the cams 604 and 606 against the thrust-receiving faces on the several core segments causes said core segments to move outwardly in

spaced relation to each other on the oblique axes of the core-former to expand said core-former. This outward movement of the core segments is guided by the keys 630 and 632 on the core segments sliding in the keyways in the spider and pilot plates 576 and 592, and by the sleeves 613 sliding in the core segment openings 612. With the core segments in this expanded position, as shown in FIG. 3, the face plates 620 bridge the spaces between the spaced pairs of adjacent core segments along the side faces of the core-former to prevent the entry of aggregate therein. And the top and bottom cover plates 624 and 625 cooperating with the spider plate 576 and pilot plate 592 prevent the entry of aggregate into the core-former from the top and bottom thereof.

To retract the core-former into its collapsed position, the shaft 580 is rotated through an angle of 90° in a counterclockwise direction as viewed in FIG. 3. This rotational movement of the shaft moves the cams 604 and 606 into the recesses 602 in the core segments 582B and 582A respectively. With the cams out of engagement with the thrust-receiving faces on the core segments, said core segments are pulled inwardly toward their collapsed positions by the plurality of springs 616. Such inward movement of the core segments is also guided by their respective keys sliding in the spider and pilot plates and by the sleeves 613 in which the springs 616 are carried. During this inward movement of the core segments, the beveled edges on the face plates and the spider and pilot plates will slide along the outer faces of the core segments to screed any aggregate therefrom, with the beveled edges of the top and bottom cover plates 624 and 625 screeding the outer faces of said spider and pilot plates.

I claim:

1. An expandable core-former, comprising two pairs of elongated diagonally opposed core segments, said core segments being movable with respect to each other and each having a plurality of thrust-receiving faces and recesses with the thrust-receiving faces on the core segments in one pair being aligned with the recesses in the other pair and the thrust-receiving faces on said other pair being aligned with the recesses in said one pair, a first shaft movable for moving the core-former to and from an operative position in a mold and having means slidably connected to said core segments for guiding the movements thereof, a second shaft rotatably carried in said first shaft and having cam means mounted thereon and interposed between said core segments, said cam means having lobes receivable in said recesses when the core-former is collapsed and receivable against said thrust-receiving faces upon rotation of said second shaft to move said core segments outwardly for expanding the core-former, means interconnecting said core segments for moving them inwardly to collapse the core-former, and means bridging and closing the spaces between said core segments.

2. An expandable core-former as set forth in claim 1 in which said cam means comprises two sets of double lobed cams mounted on said second shaft, the lobes on one set being transverse to the lobes on the other set whereby the lobes on each set are received in the recesses in one of said pairs of core segments when the core-former is collapsed and bear against the thrust-receiving faces on the other pair of core segments to expand the core-former when said second shaft is rotated in core-former expanding direction.

3. An expandable core-former as set forth in claim 1 in which said thrust-receiving faces and recesses are alternately disposed on each of said core segments, and said cam means comprises two sets of double lobed cams, the cams in each of said two sets of cams being alternately mounted on said second shaft in offset relation to each other with the lateral faces of each of said cams interposed between the cam lobes being curved inwardly and disposed in abutting relation with a pair of said thrust-

receiving faces when the core-former is in collapsed position, said thrust-receiving faces having the same curvature as said lateral cam faces.

4. An expandable core-former as set forth in claim 1 in which said means interconnecting the core segments comprises a plurality of sleeves fixedly mounted in each of said core segments and slidably received in an opening formed in an adjacent core segment, and a spring carried in each of said sleeves and connected to a pair of adjacent core segments.

5. An expandable core-former, comprising two pairs of elongated diagonally opposed core segments, said core segments being movable with respect to each other and each having a plurality of thrust-receiving faces and recesses with the thrust-receiving faces on the core segments in one pair being aligned with the recesses in the other pair and the thrust-receiving faces on said other pair being aligned with the recesses in said one pair, a first shaft movable for moving the core-former to and from an operative position in a mold, a plate fixedly mounted on said first shaft and slidably connected to the upper ends of said core segments, a second shaft rotatably carried in said first shaft and having cam means mounted thereon and interposed between said core segments, said cam means having lobes receivable in said recesses when the core-former is collapsed and receivable against said thrust-receiving faces upon rotation of said second shaft to move said core segments outwardly for expanding the core-former, means interconnecting said core segments for moving them inwardly to collapse the core-former, a pilot plate rotatably connected to the lower end of said second shaft and slidably connected to the lower end of

said core segments, a pilot on said pilot plate for releasably retaining said core-former in a fixed non-rotatable position in a mold, and means bridging and closing the spaces between said core segments.

5 6. An expandable core-former as set forth in claim 5 in which said means bridging and closing the spaces between said core segments comprises a plurality of face plates on said core segments each extending over the outer faces of a pair of adjacent core segments, and cover plates on the ends of said face plates extending over said plate and pilot plate.
